UNITED STATES PATENT OFFICE.

LUDWIG MELCHIOR AND FRIEDRICH MEYER, OF WILMINGTON, DELAWARE.

STONE-SAWING-MACHINE GAGE.

SPECIFICATION forming part of Letters Patent No. 397,244, dated February 5, 1889.

Application filed March 20, 1888. Serial No. 267,918. (No model.)

To all whom it may concern:

Be it known that we, LUDWIG MELCHIOR and FRIEDRICH MEYER, of Wilmington, in the county of New Castle and State of Delaware, have invented new and useful Improvements in Stone-Sawing-Machine Gages, of which the following is a specification.

Our invention is an improvement in stone-sawing machines, and particularly in that class of such machines in which a gang of saws is secured in a reciprocating frame; and the invention consists in the novel construction and combinations of parts, as will be hereinafter described and claimed.

As the constructions for supporting, adjusting, and operating the reciprocating frame form no part of the present invention, it is not necessary to show or describe the same herein.

In the drawings, Figure 1 is a perspective view of the improvements. Fig. 2 is a sectional view on about line xx , Fig. 1. Fig. 3 is a detail view of one of the hook-bolts. Fig. 4 is a detail view of one of the clamps. Fig. 5 is a detail view of one of the guides, and Fig. 6 is a detail view of the bracket intended for use with frames having square side bars.

The frame A may be of ordinary construction, as shown, with side bars, B, and end bars, C, the latter being slotted longitudinally for the passage of the hook-bolts D, which secure the saws E in the frame, so the said saws may be adjusted laterally to set them toward or from each other, as desired.

In this class of machines it has been common heretofore to place between the saws, immediately inside of the end bars, C, blocks, which serve to keep such saws properly apart, and such blocks may be provided in different sizes, so the saws may be held different distances apart. Our improvements avoid the necessity of these filling-blocks and provide for bracing and guiding the saws in sawing short stones at points between the ends of the frame, and preferably between the opposite ends of the short work or stones and the ends of the frame. To this end we provide the brace-bars G, which extend between the sides of the frame, and are connected at their ends adjustably to the side bars thereof. In connecting the ends of the cross-brace bars to the sides of the saw-frame we prefer to em-

ploy clamps H. In Figs. 1, 2, and 4 these clamps H are shown as provided near their upper ends with sockets h, to receive the ends of the cross-bars, and with screws h', to secure them to said cross-bars, while their lower ends curve outward at h² and are provided with screws h³. In use the said clamps are placed on the bars G, with the ends of the latter projected sufficiently to rest on the side bars, B, the portions h² of the clamp projecting out under the bars B, and the set-screws h³, turning against the said side bars, serve to keep the cross-bars in any desired adjustment along the side bars. This form of clamp may be used on square side bars, B, as well as round ones; but it is preferred to use it only on the round side bars, and to use the bracket shown in Fig. 6 when the side bars, B, are square. The said bracket (shown in Fig. 6) has arms 1 and 2, to project above and below the side bars, B, which arms support screws 3, by which the clamp may be held to the side bars. This clamp, like that shown in Fig. 1, has a socket, h, and set-screw h', to receive and secure the cross-bar. The cross-bar is preferably formed with a rib or rail, g, extended along its upper edge, and it is graduated according to any suitable scale, so the adjustable guides, presently described, may be accurately set thereon, as may be desired.

The guides I are fitted on and adjustable along the cross-bars G. In the construction shown the guides have openings i, through which the cross-bars G are passed, and set-screws i' serve to secure the said guides in any suitable adjustment on the cross-bar. By preference these guides are formed below the cross-bar, with downwardly-facing shoulders I', which form bearings for the upper edges of the saws.

Heretofore in the sawing of short stones the saws, when operated under any considerable weight or at all fast, have been found to bend, twist, and buckle, so that to practically saw such short stones it has been necessary to run the saws under very little weight and at a low rate of speed, rendering the operation slow, and consequently expensive. Our invention obviates this by providing guide-braces, comprising the cross-bars and the

guides thereon, between the ends of the saw-carrying frames, and in practice arrange such guide-braces on opposite sides of the stone or work to be accomplished—that is to say, between such work and the ends of the saws—so the saws will be braced and may be operated rapidly and under considerable weight, as is desired.

When long work is being cut, the guides or braces may be moved to the ends of the saw-blades close to the inner faces of the end bars, C, of the frame.

It will be seen that as the frame A lowers, the saws have to go down also, as the guides and braces hold the saws to the frame, so that no upward curving or arching of the saws is possible, thus insuring a speedier sawing, as well as causing the saws to make a cleaner cut, as will be understood.

Having thus described our invention, what we claim as new is—

1. An attachment, substantially as described, comprising a cross-bar, guides thereon, and clamps having near one end sockets in which the ends of the cross-bar may be secured, and having their lower ends curved outward and provided with a clamping-screw, substantially as set forth.

2. In a stone-sawing apparatus, the combination, with the frame having side bars, of the cross-bar having guides for the saws, the clamps having openings fitted to receive the cross bar, such clamps being adjustable along

the side bars of the frame, and set-screws for securing the clamps in any suitable adjustment along said side bars, substantially as set forth.

3. The herein-described improvement in stone-sawing apparatus, comprising a cross-bar provided with guides for the saws, and clamps connected adjustably with the ends of said cross-bar, said clamps being provided with set-screws, whereby they may be secured in any suitable adjustment along the side bars of the saw-carrying frame, substantially as set forth.

4. In a stone-sawing apparatus, a cross-bar provided with guides secured on and adjustable therealong, such guides being provided on their sides with downwardly-facing shoulders, substantially as and for the purposes specified.

5. The improved stone-sawing apparatus consisting of the frame having side bars, B, the cross-bars, the clamps having openings fitted to receive the cross-bars and provided with set-screws, whereby they may be secured in any suitable adjustment along bars B, and the guides having on their sides downwardly-facing shoulders, substantially as set forth.

LUDWIG MELCHIOR.
FRIEDRICH MEYER.
